UNITED STATES PATENT OFFICE.

JACOB L. SNIDER, OF HARROD, OHIO.

SEARCHED.

1,134,646.

Specification of Letters Patent.

Patented Apr. 6, 1915.

Application filed July 30, 1912. Serial No. 854,160.

To all whom it may concern:

Be it known that I, JACOB L. SNIDER, citizen of the United States, residing at Harrod, in the county of Allen and State of Ohio, have invented certain new and useful Improvements in Game-Boards, of which the following is a specification.

This invention relates to games, the object of the invention being to improve the game of bagatelle, and consequently to increase the interest therein, the invention consisting essentially, of a board, a plunger, a ball or marble to be projected through manipulation of the plunger, a numbered revolvable disk, an indicator, and a pendulum or arm, the latter being actuated through operation of the plunger to revolve the disk, all as will be hereinafter more fully described and specifically pointed out in the claims.

In describing my invention in detail reference will be had to the accompanying drawings wherein like characters denote like or corresponding parts throughout the several views, and in which:

Figure 1 is a plan view of a game board constructed in accordance with the present invention; Fig. 2 is a longitudinal sectional view; and Fig. 3 is a cross sectional view.

Referring now to the drawings by numbers, 1 designates a game board, the ends 2 and sides 3 of which are of a height sufficient to retain the ball or marble 4 with which the game is played confined to the playing surface of the board. At one end, the board is divided off into a plurality of stalls 5, each being numbered as shown. Depressions or openings 6 are formed in the playing surface of the board adjacent the stalls 5, each depression or opening being numbered as shown. When in use, one end of the board is slightly elevated so as to dispose the playing surface thereof at an inclination whereby to cause the ball 4 subsequent to its projection in a manner to be hereinafter fully disclosed, to roll toward that end of the board having the depressions 6 and stalls 5 formed therein. It is in one of these depressions 6 or stalls 5 that the ball finally settles, the number adjacent the stall or depression into which the ball settles being the number of points gained by the party playing the game. This feature will be more fully disclosed as the description proceeds.

Disposed at a slight inclination relatively to the playing surface of the board 1 is a

guide tube 7 within which a plunger 8 is operated, the latter being spring actuated as indicated at 9 and in a manner common to the art whereby to project the ball 4. One end of the tube 7 is opened, and the opposite end closed, the closed end serving as an abutment for the spring 9 and also as an abutment for the knob 10 of the plunger, the latter being pulled against the tension of the said spring to shoot or project the ball.

A figure 11, fashioned to represent a man, is arranged upon the playing surface of the board in front of the open end of the tube 7 but slightly at one side thereof so as to dispose an arm or pendulum 12 of the figure directly in the path of the ball 4 as it is projected from the tube. The arm or pendulum 12 is flattened as indicated at 13 so as to increase the contacting surface or that portion with which the ball 4 is engageable.

At a point adjacent the forward end of the tube 7 and at one side thereof is an upright or standard 14 at the top of which is mounted a numbered revolvable disk 15, the said disk operating in a vertical plane, that is with its axis of rotation extending horizontally or across the board. The numbered surface of the disk 15 is provided with a plurality of uniformly spaced projections 16, the said projections extending or rotating in the path of rotation of the arm or pendulum 12. As the said arm 12 is actuated by reason of engagement of the ball 4 therewith, it, the said arm, engages one of the projections 16 of the disk, causing the said disk to be rotated, an indicating element 17 extending upwardly from the standard 14 over the periphery of the disk so as to designate or indicate when the said disk comes to a stand-still subsequent to actuation, the number of points gained by the party playing by reason of the rotation of the disk and the numbers delineated thereon.

From the foregoing, taken in connection with the accompanying drawings it is apparent that points are ascertained not only in the usual manner, that is, by the ball 4 settling in one of the depressions 6 or stalls 5, but also through actuation of the disk 15, the latter being rotatable in the manner above described.

In reduction to practice, I have found that the form of my invention, illustrated in the drawings and referred to in the above description, as the preferred embodiment, is

the most efficient and practical; yet realizing that the conditions concurrent with the adoption of my device will necessarily vary, I desire to emphasize the fact that various 5 minor changes in details of construction, proportion and arrangement of parts may be resorted to, when required, without sacrificing any of the advantages of my invention, as defined in the appended claims.

10 Having thus fully described my invention, what I claim as new and desire to secure by Letters Patent, is:—

15 1. A game board including a rotatable member, a disk positioned in the path of rotation of said member, said disk being rotatable by contact of the member therewith, and means to rotate the member.

20 2. A game board including a member rotatable in a vertical plane, a disk positioned in the path of said member, said disk being rotatable by contact of the member therewith, a projectile, and means directing the projectile against the said rotatable member to actuate the latter, as and for the purpose 25 set forth.

25 3. A game board including a rotatable arm, a numbered disk positioned in the path of movement of said arm, an indicator stationary with respect to said disk, said disk being rotatable by contact with the arm therewith, and means to rotate the arm.

30 4. A game board including a spring actu-

ated plunger, a projectile actuatable through manipulation of the plunger, a revoluble disk operating in a substantially vertical 35 plane, a rotatable member positioned in the path of the projectile, said member being actuatable by reason of engagement of the projectile therewith, said member when actuated moving in the path of a circle and 40 engaging said disk for rotating the latter, as and for the purpose set forth.

5. A game board including a spring actuated plunger, a projectile actuatable through manipulation of the plunger, a numbered 45 revoluble disk operating with its axis of rotation extending across the board, a plurality of projections upon the numbered face of the disk, an indicator positioned to extend over the periphery of the disk, an arm 50 positioned in the path of the projectile, said arm being rotatable through engagement of the projectile therewith, the said arm when rotated being engageable with the projections of the disk to actuate the latter to vary 55 the position of the numbers thereon relatively to the indicator associated therewith, as and for the purpose set forth.

In testimony whereof I affix my signature in presence of two witnesses.

JACOB L. SNIDER.
